UNITED STATES PATENT OFFICE.

WILLIAM J. LILLY, OF BUTTE, MONTANA.

ALARM FOR HOISTING-ENGINES.

1,239,409.

Specification of Letters Patent. Patented Sept. 4, 1917.

Original application filed April 2, 1914, Serial No. 829,019. Divided and this application filed August 5, 1915. Serial No. 43,799.

To all whom it may concern:

Be it known that I, WILLIAM J. LILLY, a subject of the King of Great Britain, and a resident of Butte, in the county of Silverbow and State of Montana, have invented a new and Improved Alarm for Hoisting-Engines, of which the following is a full, clear, and exact description.

My invention relates to alarm mechanism and more particularly to devices of this character, intended for use in connection with hoisting engines and controlling mechanism for the same.

Stated more specifically, my invention comprehends an electric alarm mechanism adapted for use in connection with controlling mechanism of the kind described in my allowed application, Serial No. 829,019 filed April 2, 1914, of which the present application is a division.

My improved alarm mechanism is mostly associated with apparatus employed to prevent overspeeding of the hoisting mechanism carrying the skip or cage as the case may be.

My alarm mechanism is also closely associated with apparatus controllable partly by the speed of the hoisting mechanism and partly by relative positions assumed by various movable parts for stopping the hoisting engine and applying the brake mechanism in the event that the operator fails, from any cause, to check the speed of the hoisting mechanism when the skip or cage reaches the proximate limit of its travel either upward or downward.

Reference is made to the accompanying drawings forming a part of this specification and in which like letters indicate like parts.

Figure 1 is a side view partly in elevation and partly diagrammatic showing generally a hoisting engine and brake mechanism associated therewith as used in connection with my improved alarm mechanism;

Fig. 1^a is a detail view showing in perspective various parts of the weight-controlled tripping device for stopping the hoisting mechanism;

Fig. 2 is a detail view partly in side elevation and partly in section showing the speed-controlled mechanism for throwing the tripping device into action and for in-

dicating by my improved alarm mechanism any danger due to overspeeding;

Fig. 2^a is a diagram of the electric circuit of the alarm mechanism;

Fig. 3 is a front elevation of the mechanism shown in Fig. 2.

Owing to the fact that my improved alarm mechanism and parts immediately associated therewith are used in connection with various parts of the hoisting engine and the controlling mechanism therefor, I will first briefly describe the structure and action of these parts.

The hoisting engine is shown at 4, the throttle valve at 5, the throttle mechanism at 6, and the throttle shaft at 7. Mounted rigidly upon this throttle shaft, is an arm 8. An actuating bar 9 is provided at one of its ends with a link 10, the latter fitting slidably upon a pin 11 carried by the arm 8. When the actuating bar 9 is moved obliquely downward in the general direction of its length, the throttle mechanism is actuated and the engine is stopped.

Various movable parts of the engine are shown at 12, and at 13 is a connecting rod for actuating the throttle mechanism independently of the actuating bar 9. A lever 14 is disposed adjacent a platform 15, serving as the engineer's stand, and the lever 14 is connected with the rod 13.

The brake drum, forming a part of the hoisting mechanism, is shown at 16. The brake shoes appear at 17, and connected with them are brake levers 18. The brake shoes are supported upon rocking arms 19, having the usual or any preferred form. Connected with the brake levers 18 are rods 20, which are also connected to a lever 21 which is journaled upon a pedestal 22. Pivotally connected to the lever 21 is a connecting rod 23, the latter being also connected by a pivot 24 with the sliding head 95 of a brake engine 25. This brake engine may be substantially of the usual or any desired construction.

The brake drum 16 provided with gearing 26, the latter being connected with a revolvable shaft 27, this shaft being connected by various geared members such as 28, 29 with a countershaft 32. This countershaft is mounted in bearings 34 and carries a bevel

gear 31 and a worm 33, both rigid upon the shaft. A worm gear 35 meshes with the worm 33, and is driven slowly thereby. Mounted rigidly upon a shaft 29^a is a bevel pinion 30, which engages and is driven by the bevel gear 31. The shaft 29^a also carries at its upper end a gear wheel 36, which meshes with another gear wheel 37, the latter being mounted within a spider 38, constituting the upper portion of the frame work. Supported by this spider, is a sleeve 39. A centrifugal speed governor 40 is supported by the spider 38 and sleeve 39, and is provided with a governor rod 41, slidably mounted and adapted to play vertically. The spider 38 is supported by frame work 42, the latter being provided with a cylindrical bearing 43. Extending through this bearing and loose relatively to the same is a sleeve 44 which serves the purpose of a hollow shaft. Encircling this hollow shaft and loose relatively to the same is a spider 45 provided with spokes 45^a and with a hub portion 45^b, these parts having together the proximate form of a large wheel, as may be understood from Figs. 2 and 3.

The worm wheel 35 is secured rigidly upon one end of a tubular shaft 46, which extends through the sleeve 44, and is loose relatively to the latter.

The spider 45 is provided with an annular rack 47 carrying rack teeth 48 extending radially inward. The spider 45 is further provided with a reduced annular portion 49, integral with it and with the annular rack just mentioned, for the purpose of supporting the latter.

Fitted upon the annular rack 47 is a slide 50, provided with a number of notches 51 (see Fig. 3), these notches being disposed at different distances measured radially outward from the axis of the annular rack 47. The slide 50 is further provided with a lug 52, integral with it, and with a set screw 53 for clamping the slide rigidly upon the annular rack. By loosening the said screw 53, the slide 50 may be adjusted relatively to the annular rack 47, and when thus adjusted may be secured in position by tightening the said screw.

Another slide 54, somewhat similar to the one just mentioned, is provided with a set screw 55, notches 56, and a lug 57. This slide is adjustable relatively to the annular rack 47, but its notches 56 are upon the opposite side of the lug 57 as compared with the position of the notches 51 relatively to the lug 52.

Extending entirely through the tubular shaft 46 is a rod 58, the outer end of this rod being connected by a bearing 59 to an arm 60, this arm being journaled upon a pin 61. Integral with the arm 60 is another arm 62, these two arms together forming a bellcrank lever. Connected with this bellcrank lever

is a pawl carrier 63, carried by and movable relatively to an arm 64. The pawl carrier 63 is adapted to be moved radially inward or outward. An arm 64 is provided with a hub 64^a fitting tightly upon the tubular shaft 70 46 and carrying a head 64^b, a pin 64^c is mounted upon this head and supports a lever 64^d. This lever, as shown in Fig. 2, carries a weight 64^e and is by a pivot pin 64^f pivotally connected with the pawl carrier 75 63. A pawl 65, having in this instance, the form of a trident head, is by aid of a pivot pin 66, mounted upon the upper end of the pawl carrier 63, and has a slight rocking movement relatively to said pawl carrier. 80

The rod 58 is connected by a bearing 67 (see Fig. 2) with the lower end of a bellcrank lever 68, this lever having an arm 69 extending horizontally. Pivotally connected with the arm 69 is a link 70. This link is 85 also pivotally connected to a pin 71, carried by the governor rod 41. A weighted lever 72 extends into engagement with the lower end of the governor rod 41, and is movable by the vertical movements of this governor 90 rod. The bellcrank lever 68 is supported upon a pin 69^a which is carried by a crank 69^b, the latter being secured rigidly upon a shaft 73, which is journaled in the frame work. Secured rigidly upon the shaft 73 95 and extending upwardly therefrom is an arm 74, provided with a number of holes 75. An actuating bar 76 is connected with the arm 74, and is adjustable by aid of the holes 75. The actuating bar 76 is provided with 100 an adjustable link 77, which may be secured in two positions relatively to a pin 77^a. The bar 76 is operated by hand, for the purpose of actuating the arm 74, and of leaving the latter in either of two normal positions. At 105 78 and 79 (see Fig. 1) are shown various levers and other movable parts, connected with the hand levers 14 and 14^a, and therefore under control of the engineer.

The weight 87, under control of the brake 110 engine, is connected with the main brake lever 21 for the purpose of actuating the latter, and thus setting the brake.

Journalized within a pedestal 83 is a shaft 82 (see Fig. 1^a) carrying an arm 81, 115 mounted rigidly upon it and pivotally connected with the actuating bar 9. The shaft 82 also carries an arm 84, and connected to this arm and movable by it, is a rod 85 for controlling the brake engine and causing 120 the brake mechanism to set. Arm 84 is loose relatively to the shaft 82 but is normally held rigidly in relation thereto by an arm 82^a shown more particularly in Fig. 1^a, this arm is secured rigidly to the shaft 82 125 82^a and is provided with a pair of ears 82^b which are disposed upon opposite sides of the arm 84. Set screws 82^c extend through the ears 82^b and engage the arm 84. By turning these set screws the arm 84 may be 130

adjusted to slightly different angles upon the shaft 82. The arm 84 carries a weight 84^b and is provided with a downwardly extending portion 84^c. Lever 84^d having the 5 shape shown in Fig. 1^a is mounted upon a pin 84^e, and is adapted to rock slightly thereupon. The lever 84^d because of its use, I conveniently designate as a stop lever. It is provided with notches 84^f upon which the 10 downwardly projecting portion 84^c, of the arm 84, can lodge whenever the lever 84^d is rocked in a clockwise direction according to Fig. 1^a. The lever 84^d carries a pin 84^g, and connected to this pin is a rod 84^h, carrying 15 a weight 84ⁱ, the rod 84^h is connected to a bellcrank lever 84^j, the latter being pivoted to a rod 84^m. This rod is connected to a lever 84ⁿ which is mounted upon a pin 84^p and engages a cam 84^a, the location of this 20 cam being indicated more particularly in Figs. 2 and 3, the cam being revoluble with the arm 64. Mounted rigidly upon the shaft 82 is an arm 86 and this arm carries a weight 87 for rocking the shaft 82, the 25 arm 86 is connected with a dashpot 86^a, for preventing unduly rapid or jerky movements of the arm 86 and shaft 82. Pivots mounted adjacent the weight 87 is a lever 88, which is engaged by this weight, a bell- 30 crank lever 89, serving the purpose of a trigger, is provided with a lug 89^a which engages an adjacent portion of the lever 88, as indicated in Fig. 1^a, by bringing the parts 87, 88, and 89 into the relation indicated in 35 this figure, the lug 89^a restrains the lever 88, and the latter supports the weight 87. If, however, the bellcrank lever 89 is turned slightly in either of two directions, the lever 88 is released and disengages the weight 87 40 whereupon this weight drops and in so doing, rocks the shaft 82. The arm 84 and the rod 85 being thus moved downwardly, the mechanism is set.

The mechanism shown in Fig. 1^a operates 45 as a variable speed mechanism—that is to say, they bring about a variable action whenever the brakes of the hoisting engine are applied. Suppose that the load to be carried is midway between the top and bottom of the shaft, and that the controlling mechanism is tripped owing to overspeed of the engine, when this occurs the weight 87 drops, and shuts off the power and in doing this applies the brake. The dropping 50 of the arm 84, however, causes the end portion 84^c of this arm to rest upon the top of the stop lever 84^d so that the rocking of the shaft 82 is limited in degree, and therefore, the opening of the brake valve is only sufficient to apply the brake very slowly. Suppose again, that the load operated upon by the engine is near the top or bottom of the shaft and that the engine, therefore, begins to slow down, the cam 84^a now engages the 55 adjacent end of the lever 84^d and this actuates the rod 84^m, the bellcrank lever 84^j, and the rod 84^h so that the stop lever 84^d is caused to rock. If, now the controlling mechanism is brought into action on account of the engine failing to slow down 70 within the limits of safety, as elsewhere described, so that the load being raised or lowered approaches too closely to the top or bottom limit of its travel, the arm 84 is now free to drop to the lower one of the 75 notches 84^f, and therefore, the shaft 82 rocks to a maximum extent, the result being that the brake is immediately applied and the engine brought to the stop in the shortest possible space of time within the limits 80 of safety.

In order to actuate the bellcrank lever 89 I connect a rod 90 with it, as indicated in Fig. 1, the upper end of this rod being pivotally connected to another bellcrank lever 85 91, which at its top carries a U-shaped bearing 92. The annular rack 47 carries a pin 93 which extends into this bearing and allows the annular rack to have a slight rocking movement, but not to rotate to any considerable extent.

The frame 42 of the controlling mechanism is provided with a post plate 94 which rests upon a pedestal 95. This pedestal is provided with a threaded bearing 96 and 95 extending through this bearing is a bolt 97. By turning this bolt the entire frame work of the controller may be shifted slightly in either of two directions for the purpose of adjusting it relatively to other parts and of 100 tightening or loosening a chain if the latter be used in connection with the driving of the shaft 32, as is sometimes done. Mounted rigidly upon the frame 42 and extending laterally therefrom is an arm 99 provided 105 with an up-turned portion 100. An arm 101 is supported by this up-turned portion and is insulated therefrom. A leaf-spring 102 is mounted upon the arm 101 and engages a movable contact pin 103 extending through 110 the upper end of the arm 101. A binding post 104 communicates with the arm 101 and spring 102. A contact spring 105 is mounted upon the up-turned portion 100, and mounted upon this spring is a binding post, 115 106. The contact spring 105 carries a contact button 107 and a boss 108 of insulating material. The contact spring 105 also carries a boss 109 of insulating material which is supported by a mounting 110. Mounted 120 upon the arm 99 is a bracket 111 and this bracket supports a bellcrank lever 112 provided with a rounded portion 113. A leaf spring 114 carried by the bracket 111 tends to maintain the bellcrank lever 112 in a pre-determined normal position. The bellcrank lever 112 is provided with an end portion 115 and the worm wheel 35 carries a boss 116, for engaging this end portion, and thereby rocking the bellcrank lever 112 125 130

slightly in a contra-clockwise direction according to Fig. 2. The bracket 111 is secured upon the arm 99 by a threaded stem 117 which extends through this arm and is 5 engaged by a nut 118. Connected with the binding posts 106 and 104 are wires 119—120. The wire 120 is also connected with the bell 98. The wire 119 leads to a battery or other source of electricity and from this source 10 of electricity, a wire 121 leads to the bell 98.

The parts are so arranged that whenever the bell crank lever 112 is rocked by engagement of the boss 116 with the adjacent end portion 15 of the bellcrank lever, the contact 15 spring 105 is moved to the left, according to Fig. 2, and the contact button 107 is moved into engagement with the contact pin 103. This conveys a circuit as follows:—

Source of electricity, wire 119, binding 20 post 106, contact spring 105, contact button 107, contact pin 103, arm 101, binding post 104, wire 120 to bell 98, and wire 121 back to source of electricity. This rings the bell 98. As the boss 116 does not come into engagement with the adjacent end portion of the bellcrank lever 112 until the load operated upon by the engine approaches the limit of its travel, the ringing of the bell serves as a warning of the condition of the mechanism.

The movement of the rod 58 to the left, according to Fig. 2, may also cause the electric bell 98 to ring. The rod 58 is in alignment with the boss 108 of insulating material, so 35 that when the rod 58 is moved to the left, to the limit of its travel, it engages this boss and bends the contact spring 105 slightly to the left according to this figure. This done, a circuit is completed through the bell 98 as 40 above traced and the ringing of the bell again gives warning to the operator.

The net result is that whenever the worm wheel 35, in turning, reaches one of the limits of its travel, or whenever the engine is 45 overspeeded, the bell 98 is caused to ring and thus gives warning.

The gearing for turning the worm wheel and parts driven thereby is so arranged that the travel of the worm wheel is very slow, 50 the entire range of travel of the worm wheel being less than one complete revolution. Such being the case, the arm 64 and pawl carrier 63, together with the pawl 65, always turn less than one complete revolution in 55 either direction—the limited amount of rotation which these parts undergo representing the aggregate amount of travel of the skip or cage, or in other words, corresponding to the maximum number of strokes ever 60 made in either direction by the hoisting engine when in action for hoisting or lowering.

The parts are so arranged that when the hoisting engine runs in one direction, so as to lower the skip or cage, the arm 64, pawl carrier 63, and pawl 65, rotate in a contra-

clockwise direction according to Fig. 3. When, however, the skip or cage is being raised, the arm, pawl carrier and pawl in question rotate in a clockwise direction according to this figure.

The operation of my device is as follows:

The parts being assembled and arranged as described, the engineer starts up the hoisting engine to raise or lower the load, consisting, say, of a skip or cage. If the load 70 is to be lowered, the movement of the various revolute parts is such that the pawl 65 turns in a contra-clockwise direction according to Fig. 3, as above stated. Because 75 of this fact, the pawl 65, in moving around, tends to come into engagement with some of the notches 56—provided the speed is not slackened. When the engine is running at full speed, the pawl 65 will enter the notches 80 56, but if the speed of the engine be slackened, the pawl will escape the notches. If, therefore, as the load nears the lower end 85 of its journey, the engineer causes the speed of the hoisting engine to decrease, the governor 40, by actuating the various parts controllable by the governor rod 41, causes the pawl to be gradually drawn radially inward, and to thus miss the notches 56. The 90 excessive speed being thus taken care of, the pawl will still engage the lug 57, unless 95 the engine is stopped completely by the time the load reaches its destination. Unless the 100 engineer stops the engine as just mentioned, the pawl, by engaging the lug 57 or the notches 56, presses upon the slide 54 and 105 rocks the annular rack 47 slightly in a contra-clockwise direction, according to Fig. 3. This actuates the bellcrank lever 91, causes the rod 90 to be thrust downwardly, and this 110 rocks the bellcrank lever 89. The lever 88 being thus disengaged, releases the arm 86, and the weight 87 thereupon drops. This 115 rocks the shaft 82, pulls the rod 86 downwardly, and causes the throttle mechanism of the engine to be actuated so as to cut off the power. It also causes the brake to be set.

Where the load is being raised instead of lowered, the action is quite similar to that just described, except that the various revolute parts move in the opposite direction, and the pawl 65 is brought against the notches 51 or lug 52 of the slide 50, instead of against corresponding parts of the slide 54.

In the event of the engine overspeeding, 120 either in hoisting or lowering the load, the rod 58 moves to the left and coming in contact with the boss 108 forces the contact button 107 into engagement with the contact pin 103. This completes the circuit above 125 described and causes the bell 98 to ring and thus give warning of the overspeeding. If, now, the engineer fails to slacken the speed of the engine, the action of the governor mechanism causes the pawl 65 to be thrust 130

into the teeth 48, which causes the rack 47 to rock. This shuts off the power and sets the brake, thereby stopping the engine.

As the load being raised by the engine 5 nears the surface of the earth the rotation of the worm wheel 35 brings the boss 116 into engagement with the adjacent end portion 115 of the bellcrank lever 112. This rocks the bellcrank lever causing the contact 10 spring 105 to be bent to the left, according to Fig. 2 as above described, bringing the contact button 107 into engagement with the contact button 103. This closes the circuit through the electric bell which there- 15 upon rings and gives warning that the load is nearing the upper limit of its travel. The engineer is therefore warned to slow down the engine and by so doing to prevent the pawl 65 from engaging with the teeth 51 and 20 the slide 50, and thus having the control mechanism stop the engine.

When the load is intermediate its extreme positions, if at any time the speed of the engine becomes excessive, the speed gov- 25 error mechanism is actuated, the rod 58 is thrust to the left, according to Fig. 2 as above described and again the electric bell rings—this time in consequence of the overspeeding of the engine. At the instant this 30 occurs the pawl 65 is moved radially outward into engagement with the annular rack 47, the latter is thereby turned slightly and caused to actuate the various movable parts controlled by it, so that throttle is 35 actuated and the power cut off, the brake being set accordingly.

The parts are so proportioned and ar- 40 ranged that the engineer has an opportunity, after receiving a warning signal from the bell, to check the speed of the engine or to 45 shut off the power as may be. It is preferable that the signal be first given so that the engineer may have a chance to heed it, and if he fails to do so, the mechanism will be brought automatically to a standstill.

I do not limit myself to the precise mech- 50 anism shown, as variations may be made therein without departing from the spirit of my invention.

Having thus described my invention what I claim as new and desire to secure by Let- 55 ters Patent is as follows:

1. In a hoisting engine, control mecha- 60 nism actuated by the engine, governor con-

trolled mechanism for modifying the action 55 of the engine actuated control mechanism, and an alarm mechanism adapted to be operated by both the engine and the governor controlled mechanisms.

2. In a hoisting engine, engine operated 60 control mechanism, governor controlled mechanism, means for connecting the gov- 65 ernor controlled mechanism with the engine operated control mechanism under ex- cessive speed conditions, and an alarm mech- 70 anism adapted to be operated by either one or both the engine or governor controlled mechanisms.

3. In a hoisting engine, an engine oper- 70 ated control mechanism embodying a mov- 75 able member and a plurality of differently positioned stops carried by said movable member, governor controlled mechanism in- 80 cluding an element movable thereby into the path of some one of the aforesaid stops, 85 and an alarm mechanism adapted to be op- 90 erated by either one or both the engine or the governor controlled mechanisms.

4. In a hoisting engine, an engine oper- 80 ated control embodying a movable member 85 and an element mounted upon said member and movable therewith and embodying a plurality of stops differently positioned both laterally and longitudinally, a gov- 90 ernor controlled mechanism including an element movable thereby into the path of some one of the said stops, and an alarm mechanism adapted to be operated by either one or both the engine or governor 95 controlled mechanisms.

5. In a hoisting engine, an engine oper- 95 ated control embodying a rotary member, a 100 block adjustably mounted upon said mem- ber and stepped to provide a plurality of stops, a governor controlled mechanism in- cluding an element to be projected into the path of some one of the said stops, and an alarm mechanism adapted to be operated by either one or both the engine or governor controlled mechanisms.

In testimony whereof I have signed my name to this specification in the presence of two subscribing witnesses.

WILLIAM J. LILLY.
